JAMES OLD, OF PITTSBURG, PENNSYLVANIA.

Letters Patent No. 87,790, dated March 16, 1869.

IMPROVEMENT IN GRATES.

The Schedule referred to in these Letters Patent and making part of the same.

To all whom it may concern:

Be it known that I, JAMES OLD, of the city of Pittsburgh, in the county of Allegheny, and State of Pennsylvania, have invented a new and useful Improvement in Grates and Fire-Places; and I do hereby declare the following to be a full, clear, and exact description thereof, reference being had to the accompanying drawing, making a part of this specification, in which—

Figure 1 is a front elevation of my improved grate and fire-place;

Figure 2 is a vertical section through $x-x$, fig. 1; and

Figures 3 and 4 are end views of the grate, with devices attached for stirring the fire, and showing the same in different positions.

Like letters of reference indicate like parts in each.

My invention relates to an improved construction of fire-place and grate; and

It consists—

First, in closing the under side of the grate with a rocking or tipping damper-plate, furnished with projecting agitators, which play upward between the grate-bars, to stir the fire and disengage the ashes.

Second, in attaching, between the rear part of the grate and the back wall, a lifting-bar, by which to stir the fire in that part of the grate, and open apertures for the admission of air thereto.

Third, in the construction of devices for operating such damper-plate, agitators, and rocking, or lifting-bar.

To enable others skilled in the art to make and use my invention, I will proceed to describe its construction and manner of use.

a represent the side, and

a' , the rear walls of a fire-place, furnace, or stove, of any usual or known construction.

The grate, or fire-basket b , is also of the ordinary construction, and supported by the side walls in the usual way, but it does not extend quite to the back wall.

Along under the bottom of the grate b , extends the damper-plate c , and from this, the agitators c' extend upward between the grate-bars b .

From either end of this plate c , or at any other desirable points, the shanks e extend back, are pivoted to the rear part of the grate b , and, by their rear ends, support a lifting-bar, e' . This lifting-bar e' closes the aperture between the rear part of the grate and the back wall d of the fire-space.

In order to operate the agitators c' and tipping-bar e' , I use a device, particularly shown in figs. 1, 3, and 4.

The lever m has a head, s , which is pivoted at one point to a lug, o , projecting from one of the bars b' , and, at another point, has a bolt, o' , passing through a slot in one of the agitators c'' , (figs. 1 and 4.)

By raising the lever m , as in fig. 4, the bolt o' passes to the rear of the slot in the agitator c'' , depresses the damper-plate b , elevates the lifting-bar e' , loosens the

fuel in the back part of the grate, and opens the whole bottom and rear part of the grate to the admission of air. Combustion is consequently kept up in the rear part of the fire-space, next the tile d , by which the latter is heated, a uniform fire kept up throughout the fire-space, and, consequently, more heat secured from a fire-grate of any given size.

By moving the lever up and down a few times, the fuel in the grate is well shaken up, and the ashes out into the ash-pit g .

If the fire be too great, the lever m is lowered, as shown in fig. 3, and then the plate c cuts off the supply of air under the grate, and the tipping-bar e' closes the vent in the rear.

On the under side of the lifting-bar e' , I make a series of projections, x , which, when the bar is tilted up, act like grate-bars, to prevent the fuel from falling through the aperture thus formed between the bar e' and the tile d .

By the use of such devices, when desired, a complete combustion of the fuel can be secured throughout the fire-basket, with the evolution of the maximum of heat; or, by merely shifting a lever, the grate can be so completely shut up that combustion will be at once and almost entirely arrested, and the fire kept from either expiring or burning out for a considerable time.

The centres of motion, o and o' , and the slot in the agitator b' , are so related to each other, that the lever m locks the devices either open or shut, as the case may be.

It will be observed, that with the construction and mode of operation described, the agitators c' are removed from the fire when a vivid combustion is required, whereby they are preserved from the destructive action of the fire thereon, and, in this respect, they differ from other devices already in use for the same purpose.

What I claim as my invention, and desire to secure by Letters Patent, is—

1. A tilting damper-plate c , with agitators c' on its upper face, which extend up and operate between the bars b , in combination with a lever, m , and head, s , so connected by a wrist and slot with such damper-plate, as to lock it open or shut, or vibrate it at pleasure, substantially as and for the purposes above set forth.

2. A lifting-bar, e' , pivoted between the rear part of a fire-grate and the back wall of the fire-space, for regulating the combustion in the rear part of the fire, constructed and operated substantially as and for the purposes hereinbefore set forth.

In testimony whereof, I, the said JAMES OLD, have hereunto set my hand.

JAMES OLD.
